UNITED STATES PATENT OFFICE.

EDWIN R. FELLOWS, OF SPRINGFIELD, VERMONT.

MACHINE FOR GRINDING GEAR-GENERATING CUTTERS.

SPECIFICATION forming part of Letters Patent No. 686,599, dated November 12, 1901.

Application filed June 24, 1899. Serial No. 721,711. (No model.)

To all whom it may concern:

Be it known that I, EDWIN R. FELLOWS, of Springfield, in the county of Windsor and State of Vermont, have invented certain new and useful Improvements in Machines for Grinding Gear-Shaped Articles, of which the following is a specification.

This invention relates to the production of gear-shaped articles such as gear-generating cutters of the character described in United States Letters Patent No. 579,570, granted to me March 30, 1897, said patent describing a metal-planing cutter having a continuous circular series of radiating or outwardly-projecting metal-planing teeth of uniform size, whose cutting edges are at the ends of the teeth on the face of the cutter, the backs of the teeth being inclined at a slight clearance-angle to the axis of the cutter to give the cutter the clearance of metal-planing tools.

A cutter of the character specified is adapted for use in generating-gears by the method described in United States Letters Patent No. 579,708, granted to me March 30, 1897, which show a machine in which are combined a metal-planing cutter having a circular series of radiating or outwardly-projecting gear-shaped metal-planing teeth, a blank holder or support, means for reciprocating one of said parts to cause the cutter to plane the blank across its edge, and means for changing the relative position of said parts to cause the teeth to act successively at different points on the blank and generate the gear-teeth thereon, the operation of generating the curves of a plurality of teeth being simultaneously carried on.

The present invention has for its object to provide a machine for finishing cutters of the character described—that is, for treating a cutter-blank which has had its teeth previously roughed out and hardened in such a manner as to bring said teeth to their correct size and shape. The invention is not, however, limited in its application to finishing gear-shaping cutters, as it may also be employed in grinding the teeth of bevel and other gears which have been hardened and are hence difficult to attack by means of a metal-planing tool.

The invention involves the employment of an abrasive generating-wheel, a holder for

the cutter, means for imparting a rolling motion to said holder to cause it to roll over and bring one of its teeth to contact with the face of the generating-wheel, whereby the side of the tooth is ground to its correct curvature, and means for indexing the cutter-holder or turning it on its own axis to bring the teeth of the cutter successively into position to be ground.

Of the accompanying drawings, Figure 1 represents a front elevation of a simple form of machine embodying my invention. Fig. 2 represents a plan view thereof. Fig. 3 represents a longitudinal section therethrough on the line 3 3 of Fig. 1. Fig. 4 represents a front elevation, partly in section, showing a more elaborate embodiment of my invention in the form of an automatic machine, the cutter being shown as retracted from the grinder. Fig. 5 represents a view similar to the foregoing with parts in section, the cutter being shown in contact with the grinder. Fig. 6 represents a plan view of the machine. Fig. 7 represents a rear elevation with parts broken away and parts in section. Fig. 8 represents a section on line 8 8 of Fig. 5. Fig. 9 represents a right end elevation. Fig. 10 represents a detail plan view of the cylindrical roller and tapes governing the cutter-spindle. Fig. 11 represents a transverse sectional view of said roller with its slide and adjacent parts. Fig. 12 represents a left end elevation of the machine. Fig. 13 represents a detail plan view of the diamond-holder and adjacent parts employed in facing the grinder, said device being omitted in certain previous figures for the sake of clearness. Fig. 14 represents a side elevation of said parts. Fig. 15 represents a view corresponding to Fig. 11, showing a modification, hereinafter referred to, for moving the roller tape-bars.

The same reference characters indicate the same parts in all the figures.

Referring for the present to Figs. 1, 2, and 3, *a* designates the base or frame of the machine, and *b* designates the spindle or arbor, to the end of which the cutter *c* is clamped. The cutter is held between a shoulder *b*⁸ on the spindle and a ring or washer *b*⁹, against which a nut *b*¹², engaging the threaded end of the spindle, is screwed.

d designates a generating-wheel, such as an

emery-wheel, for grinding the cutter-teeth, said wheel having an edge thin enough to enter into the spaces between the teeth of the cutter and an acting face 2 in a plane at right angles to the axis of the wheel. The wheel is attached to a spindle d' , which is mounted in a bearing-sleeve d^2 and has a belt-pulley d^3 at its rear end, whereby rotatory movement may be applied to the wheel.

- 10 The cutter c is of the form referred to, having radial or outwardly-projecting gear-shaped teeth $c' c'$, the cutting edges of which are on their front ends 5 and the crests 6 of which are inclined at a slight angle to the axis of the cutter, giving the teeth the clearance of ordinary metal-planing tools, while the sides 7 of the teeth when ground will have a convergence which gives them side clearance, there being thus imparted to the cutter 15 the general form of a bevel-gear. The large end of the cutter is preferably slightly dished to give the teeth the ordinary rake of metal-planing tools.

In carrying out my invention as hereinabove described I employ the principle of generating an involute tooth by the action of an imaginary rack having teeth of the form of a truncated wedge. The face 2 of the emery-wheel d corresponds to the side of one tooth 20 of the rack.

The spindle b , which carries the cutter, is mounted in an elongated bearing-sleeve b' , which has two conical surfaces 3 and 4 turned on it near its front and rear ends and forming parts of the pitch-cone of the bevel-wheel-shaped cutter. These surfaces are adapted to roll on two flat bars $a' a^2$, attached to the frame a and forming a supporting plane surface for the cone, and between the conical 25 surfaces and the bars are interposed two pairs of thin flat tapes or bands $e e' e' e$, preferably made of steel, so as to be inextensible and attached at their inner ends to the sleeve b' by screws $e^2 e^2$ and at their outer ends to the bars $a' a^2$ by screws $e^3 e^3$. When rolling 30 motion is imparted to the sleeve, one tape in each set winds up on the sleeve while the other tape unwinds, thus causing said sleeve and the cutter to turn on their own axis, the resultant being a rolling motion with the apex 35 of the pitch-cone as a center. During this movement the axis of the spindle b generates a conical surface. Endwise play of the sleeve is prevented by a spring b^2 , surrounding the 40 same and abutting at its rear end against a shoulder on the sleeve and at its front end against a loose collar b^3 , which abuts the tape-bar a' .

b^4 is a collar keyed to the rear end of the 45 sleeve b' , and b^5 is a handle projecting therefrom and adapted to be grasped to impart the rolling movement to the sleeve. Said rolling movement results in reciprocating the cutter c toward and from the emery-wheel d . On 50 the movement of the cutter toward the emery-wheel the side of one of its teeth c' will roll over into contact with the face 2 of said wheel,

and the latter will grind an involute surface thereon. If the upper surfaces of the tape-bars $a' a^2$ were parallel to the axis of the emery-wheel, the curve generated on the tooth would be that mating with a rack having square teeth or teeth of no angle; but in order to give the cutter-teeth their proper obliquity I incline the tape-bars at an acute angle to the axis of the emery-wheel, as shown in Fig. 1, which is equivalent to inclining the imaginary rack of which the emery-wheel represents one tooth. When the emery-wheel reaches the root of the cutter-tooth, its face 2 is radial with the center of the cutter c , as represented in Fig. 1.

On the rear end of the cutter-supporting spindle b is secured an indexing-wheel f , provided with teeth around its periphery meshing with a worm f' , having a spindle f^2 , mounted in bearings on a bracket b^6 , which depends from the collar b^4 , rigidly keyed on the sleeve b' . For rotating the worm a short crank f^3 is attached to its spindle, said crank carrying at its end a locking-pin f^4 , adapted to enter a hole in a projecting boss b^7 on the collar b^4 to lock the worm. Each time the cutter c is rolled back out of contact with the emery-wheel the locking-pin f^4 is withdrawn and the index-wheel f rotated to turn the spindle b on its axis and bring a fresh tooth of the cutter into position to be ground. The pitches of the index-wheel and of the worm are so related that a given number of revolutions of the crank f^3 will step the cutter ahead exactly one tooth and the locking-pin is employed to fix the cutter in the position thus determined. The stepping of the cutter ahead after each contact with the emery-wheel is continued until it has made a complete rotation and has had one side of each of its teeth ground. The grinding of the opposite sides of the cutter-teeth is preferably done on another machine having an arrangement of emery-wheel and inclined tape-bars the reverse of that on the machine described; but the parts of the present machine may obviously be made adjustable, so that all the grinding can be done on the one machine.

It will be evident from the foregoing description that the grinding-machine illustrated in Figs. 1, 2, and 3 may be employed in grinding hardened bevel-gears as well as gear-shaping cutters. Cutters of the kind under consideration are usually narrow, and in grinding them it is not found necessary to effect any relative longitudinal motion of the emery-wheel as a whole and the cutter. The wheel merely sweeps over the surface of the cutter-tooth; but in adapting the machine for grinding bevel-gears I prefer to mount the emery-wheel in a movable bearing, such as shown in the drawings, so that the wheel as a whole can be moved along the tooth of a wide gear to grind the whole length of said tooth. For this purpose the bearing or sleeve d^2 supporting the emery-wheel is mounted to slide forward and back on a guide d^4 on the frame

a and is provided with a rack *d*⁵ whose teeth mesh with those of a stationarily-mounted pinion *d*⁶, turned by means of a handle *d*⁷.

Having explained the elements and operation of my invention by the description of a simple hand-operated machine constructed in accordance therewith, I now proceed to the consideration of an automatic machine embodying the invention and differing in the action of its working parts only by the substitution of a cylindrical roller carrying the cutter-holding spindle for the conical roller of the machine just described and the setting of the grinding-wheel with its plane at a slight angle to the axis of said roller to give the cutter-teeth their angle of side clearance.

Referring to Figs. 4 to 12, *a*⁴ is the machine's frame or base, the upper portion of which only is shown.

b is the cutter-spindle, having a holder on its end in which the cutter *c* is clamped, and *d* is the grinding-wheel, having an acting face 2 in a plane at right angles to its axis of rotation. The spindle *b* is carried in a bearing-sleeve *b*¹³, having a cylindrical portion 8, to which are attached oppositely-wound tapes *e* *e*, having their outer ends secured to flat-topped tape-bars *a*⁵ *a*⁶. The latter are bolted to the frame in an inclined position, as shown. The bearing-sleeve *b*¹³ is mounted in a slide *b*¹⁴, which is adapted to reciprocate in a rectilinear path of an inclination corresponding to that of the tape-bars on a suitable guide on the frame *a*⁴. The slide is reciprocated by means of a bell-crank lever *b*¹⁶, one of the arms of which is connected by a link *b*¹⁷ with the slide, the other arm being connected by a link *b*¹⁸ with a crank *b*¹⁹ on a continuously-rotating cross-shaft *b*²¹, mounted in suitable bearings on the frame. Said cross-shaft has a worm-gear *b*²² at its end, meshing with a worm *g*² on the main drive-shaft *g* of the machine, which latter is equipped with a cone belt-pulley *g*'. It is evident that the reciprocation of the slide *b*¹⁴ gives the cutter *c*, through the control exercised by the tapes *e* *e*, the motion required to roll it from the retracted position represented in Fig. 4 over into contact with the grinding-wheel *d*, as shown in Fig. 5, and back again, causing the grinding-wheel to generate an involute surface on the side of each tooth of the cutter, the cutter being automatically stepped forward or indexed, one tooth on each backward stroke, by indexing mechanism presently to be described.

The spindle *d*' of the grinding-wheel has a belt-pulley *d*³ on its rear end, whereby it may be rotated and is mounted in a bearing-sleeve *d*⁸, which is set so as to incline the plane of the acting face 2 of said wheel at a slight angle to the axial line of the cutter-spindle, as represented in Fig. 6, and thereby cause said wheel to grind the sides of the cutter-teeth with a slight convergence to give the teeth their side-cutting clearance.

By means of this machine cutters such as

the one described in an application for Letters Patent, Serial No. 721,712, filed by me June 24, 1899, can be ground. Said application describes a cutter having an endless circular series of radial or outwardly-projecting metal-planing teeth, the sides of which converge in the direction of their length and are of equal curvature throughout—that is, supposing the teeth of the cutter to be involute teeth, the side outlines of a tooth at different points along the length of the tooth will be involutes drawn to base-circles of equal diameter. In this machine the grinding-wheel is set so that its plane will follow the convergent lines of the sides of involute teeth and will grind the involute surface and be when in contact tangent thereto.

The sleeve *d*⁸ is carried by a slide *d*⁹, to which a vertical adjustment may be given by a hand-screw *d*¹² to vary the elevation of the grinding-wheel, and said slide and hand-screw are in turn carried by a plate *d*¹³, mounted to slide on the side of the frame *a*⁴ in the arc of a circle whose center is at the point occupied by the center of the cutter-spindle *b* when at its forward extreme of position, Fig. 5. By this adjustment the angle of obliquity of the grinding-wheel with respect to the cutter may be varied. The plate *d*¹³ is clamped to the frame *a*⁴ by bolts *d*¹⁵ *d*¹⁶, the bolt *d*¹⁶ also serving to clamp the slide *d*⁹ in position. A segmental tongue *d*¹⁴ on the frame *a*⁴, fitting in a correspondingly-shaped groove in the plate *d*¹³, serves to guide said plate. A third adjustment is provided for the grinding-wheel *d* by mounting the bearing-sleeve *d*⁸ so as to be capable of sliding on the slide *d*⁹ in the direction of the axis of the wheel, its position being regulated by means of an adjusting-screw *d*¹⁷, against the head of which the sleeve is pressed by a spring *d*¹⁸. This adjustment is employed when the face of the grinding-wheel is trued up by the diamond. (Illustrated in Figs. 12, 13, and 14.) The holder or bracket *h* for the diamond *h* is mounted on top of the slide *d*⁹, carrying the grinding-wheel *d*, but is normally swung aside on its pivot-bolt *h*² to the position shown in broken lines in Fig. 13. When it becomes necessary, however, to true up the acting face of the emery-wheel *d*, so as to keep said face a perfect plane, the cutter-operating mechanism is stopped and the bracket *h* is swung around and fixed in place with the bolt *h*² and an additional bolt *h*³, as represented in full lines in Figs. 12, 13, and 14. The diamond *h* should be so adjusted in its bracket that when thus positioned it coincides with the proper plane of the emery-wheel face 2. Said wheel is moved bodily in the direction of its axis by adjusting the screw *d*¹⁷ to bring the face 2 slightly past this plane, and the diamond is then moved inwardly in a radial direction over the face of the emery-wheel by manipulating a screw *h*⁴, which projects a slide *h*⁵ on which the diamond is mounted. The diamond grinds off the surface of the

wheel and reduces the face 2 to a true plane. Lateral adjustment of the diamond may be effected when required by manipulating a nut h^6 .

5 I will now describe the indexing mechanism for rotating the cutter tooth by tooth on its own axis. This rotation takes place after the motion of the slide b^{14} has withdrawn the cutter from contact with the emery-wheel and occupies about one-third of the operating time.

f is a large index-wheel attached to the rear end of the cutter-supporting spindle b and formed with teeth on its periphery which mesh with a worm f' , carried in bearings on an arm or bracket b^{23} , rigidly keyed to the rear end of the sleeve b^{13} , which supports the spindle b . Said bracket in practice is suitably counterweighted to balance the mechanism carried by it. On the shaft of the worm f' is a gear f^5 , meshing with a gear f^6 , on whose shaft is a gear f^7 , meshing with a gear f^8 , all carried by the bracket b^{23} . The shaft of the last-said gear terminates in a universal joint f^9 , which connects it with the inner section 9 of a telescopic shaft f^{12} . The outer tubular section 10 of said shaft is splined to the section 9, so that the two rotate together, and is connected by a universal joint f^{13} to a short shaft f^{14} , which is driven intermittently through gears $f^{15} f^{16} f^{17} f^{18}$, segmental gear f^{19} , and bevel-gears $f^{21} f^{22}$ from the continuously-rotating cross-shaft b^{21} . The gears $f^5 f^6$ are change-gears, which may have variously related diameters, according to the pitch of the cutter which is to be ground. The segmental gear f^{19} gives the gears f^{18} and f^{17} one complete rotation in its passage across the former of them, and they in turn give the worm f' a certain number of rotations and cause the index-gear f on the end of the cutter-spindle to make a predetermined fraction of a rotation, the amount of which depends upon the relation of the change-gears $f^5 f^6$. To the bracket b^{23} is affixed a segmental scale or index f^{23} , over which a pointer f^{24} , mounted alongside of the gear f^5 , is adapted to sweep. The collar f^{27} , Fig. 7, which bears the pointer, is normally loose on the shaft of the worm f' and gear f^5 , but may be secured thereto by means of a thumb-screw f^{25} . The pointer and scale are used to calibrate the cutter. In calibrating the thumb-screw f^{25} is set up, the gear f^6 is loosened on its shaft by throwing over a clamping-lever f^{26} , and the pointer is moved a predetermined distance across its index, which distance gives a known equivalent rotary movement to the cutter.

It now remains to consider the device for locking the indexing mechanism.

When the cutter has rolled back two-thirds of its stroke away from the emery-wheel and is out of contact therewith, the locking-pin included in said device is automatically withdrawn and the mutilated gear comes into action and rotates the indexing-worm, which rotation continues for the remainder of the

back stroke of the cutter and for one-third of its return stroke, after which the said locking-pin again becomes engaged and locks the indexing mechanism. On the same shaft with the gears f^6 and f^7 is a disk i , having a segmental portion of its periphery cut away to form two stops or abutments 15 16, with which two shoulders 13 14, located at right angles on a locking-pin i , are adapted to become engaged, thereby locking said disk, and hence the worm f' , from rotation in either direction. The pin i is mounted in guides on the bracket b^{23} and is normally pressed by a spring i^2 into engagement with the notched disk i . Release of the pin is effected by the intermittent action of a dog i^4 , mounted on a short shaft i^5 , carried by the bracket b^{23} and terminating in a universal joint which connects it with the inner section 11 of a telescopic shaft i^7 . The outer tubular section 12 of said shaft is splined to the inner section, so that the two rotate together, and is carried in a tubular bracket i^8 , pivoted at i^9 to a stud on the machine-frame a^4 . Said outer section 12 of the shaft is provided with shoulders at either end outside of its bearing in the socket i^8 , so as to be incapable of moving longitudinally therein, and on its rear end is fixed a segment of a bevel-gear i^{12} , whose teeth mesh with a bevel-gear segment i^{13} , formed on a plate i^{14} , which has the shape of a bell-crank and is pivoted on the stud i^9 . A cam i^{16} , screwed to the side of the worm-gear b^{21} , and hence revolving with the shaft b^{21} , engages a roll i^{15} on the bell-crank once in every revolution of said shaft and by such engagement oscillates the bell-crank, rotates the telescopic shaft, and withdraws the locking-pin i . As soon as the cam i^{16} leaves the roll i^{15} the pin is returned by its spring into locking engagement with the disk i .

In Figs. 4, 6, 7, and 8 the parts of the machine have the positions which they occupy when the cutter is rolled back away from the emery-wheel. As the cutter moves forward up its incline the bracket b^{23} and all the parts carried thereby are swung upwardly, so as to occupy the position shown in Fig. 5 when the cutter reaches the limit of its forward movement. During this oscillation of the bracket the telescopic shafts connecting the fixed gearing with the mechanism on the bracket will become extended.

It is evident that with the machine as thus far described cutters of but one diameter of pitch-circle can be ground, said diameter being that of the cylindrical portion 8 of the cutter-spindle roller plus the thickness of the tapes e . To grind cutters of a different pitch, the roller might be provided with cylindrical portions of different diameters and corresponding tapes and tape-bars, which bars run loose except when in use, or a mechanism for moving the tape-bars may be provided such as that illustrated in Fig. 15. The tape-bars a^5 in this arrangement are mounted to slide in the direction of their length and

are connected by a link e^4 with a bell-crank e^5 , pivoted at e^6 to the frame. e^7 is a slide-way or guide mounted on an ear b^2 on the slide b^14 and adapted to be fixed at different angles thereon. An arm of the bell-crank e^5 is pivoted to a block e^8 , sliding in the groove of said guide, and the travel of the slide b^14 has by this connection the effect of oscillating the bell-crank and moving the tape-bars in the direction of their length. By varying the angle of the guide e^7 this movement of the bars may be made greater or less, and by setting the guide e^7 angularly to either one side or the other of the path of its movement the bars may be caused to travel either in the same direction as the slide b^14 or opposite thereto. It is evident that the former movement will be equivalent to increasing the diameter of the pitch-circle on which the cutter rolls, while the latter movement will be equivalent to decreasing the pitch-circle. By substituting a curved guide for the straight guide e^7 and a roll for the block e^8 a variation of the curve ground on the cutter-tooth may be obtained. In this machine, as in the one illustrated in Figs. 1, 2, and 3, only one side of each of the cutter-teeth is ground. To grind the other sides of the teeth, a machine is employed having a converse arrangement—that is, having its slide inclined in an opposite direction to the slide b^14 and the grinding-wheel d faced the other way. This arrangement would be obtained by mounting the mechanism located on the front of the machine, as shown, on the back of the machine and, conversely, bringing the cutter at the other end of its spindle.

The principles of construction employed in the machine could be embodied in a machine for grinding the teeth of spur-gears by setting the grinding-wheel with its plane parallel to the axis of the cutter-spindle, and preferably giving either the gear or the grinding-wheel a movement longitudinally of the gear-teeth.

It will be noted that the first-described embodiment of my invention differs from the second in that the former grinds surfaces on the cutter-teeth which are those of a true bevel-gear in which the base-circles of the involutes decrease in diameter as they approach the apex of the gear, whereas the latter grinds involute surfaces, all portions of which have the same base circle or cylinder, although the general form of the completed cutter is that of a section of a fluted cone. The relative movement of the blank and grinding-wheel in the latter embodiment is that of a rack and pinion of the spur-gear system having skewed teeth.

In the foregoing description I have employed the terms "cutter" and "gear" to designate the work before it is operated on by the machine; but in all cases the work before being finished in the machine is properly to be considered as a blank which has had its teeth roughed out to more or less approximate their final form.

I claim—

1. In a machine for generating gear-teeth on hardened blanks, the combination of a blank-holder, a grinding-wheel, and mechanism for positively controlling the wheel and holder, said mechanism having provisions for relatively moving said wheel and holder in a relation wherein the grinding-wheel generates the curved outlines of gear-teeth on a blank held in the holder. 75

2. In a machine for generating gear-teeth on hardened toothed blanks, a rotatable grinding-wheel, a blank-holder, and means for imparting a relative movement to the two in the relation of intermeshing gears. 80

3. In a machine for generating gear-teeth on hardened toothed blanks, the combination of a grinding-wheel, a blank-holder, and means for rolling the blank-holder toward and from the edge of the grinding-wheel, to generate the side of a tooth on the blank by abrasion against the wheel. 85

4. In a machine for generating gear-teeth on hardened blanks, the combination of a blank-holder, a grinding-wheel, and means for imparting a relative movement to the two in the relation of intermeshing gears of the spur system. 95

5. In a machine for generating gear-teeth on hardened blanks, the combination of a blank-holder, a grinding-wheel set angularly to correspond to a skewed tooth, and means for imparting a relative movement to the two in the relation of intermeshing gears of the spur system. 100

6. In a machine for generating gear-teeth on hardened toothed blanks, the combination of a grinding-wheel having an acting face at right angles to its axis, a blank-holder, and means for rolling the blank-holder toward and from the edge of the grinding-wheel in a path inclined to the plane of its face. 105

7. In a machine for generating gear-teeth on hardened toothed blanks, the combination of a grinder, a blank-holder, a cylindrical roller supporting the holder, tapes oppositely wound thereon, and means for reciprocating said roller to cause the blank-holder to roll toward and from the grinder. 115

8. In a machine for generating gear-teeth on hardened toothed blanks, the combination of a grinding-wheel, a blank-holder, and means for rolling the blank-holder toward and from the edge of the grinding-wheel with its axis in parallelism at an angle to the axis of the cutter. 120

9. In a machine for generating gear-teeth on hardened toothed blanks, the combination of a grinder, a blank-holder, a spindle supporting the latter, a bearing for said spindle, means for rolling said bearing toward and from the grinder, a gear-wheel on said spindle, and mechanism carried by said bearing and engaging the gear-wheel for rotating the spindle in its bearing. 125

10. In a machine for generating gear-teeth on hardened toothed blanks, the combination

of a grinder, a blank-holder, a spindle supporting the latter, a bearing for said spindle, means for rolling said bearing toward and from the grinder, a gear-wheel on said spindle, mechanism carried by said bearing and engaging the gear-wheel for rotating the spindle in its bearing, a driving member mounted in a stationary bearing, and a flexible and extensible rotary connection between 5 said member and said mechanism.

11. In a machine for generating gear-teeth on hardened toothed blanks, the combination of a grinder, a blank-holder, a spindle supporting the latter, a bearing for said spindle, 15 means for rolling said bearing toward and from the grinder, a gear-wheel on said spindle, mechanism carried by said bearing and engaging the gear-wheel for rotating the spindle in its bearing, and means for locking 20 said mechanism.

12. In a machine for generating gear-teeth on hardened toothed blanks, the combination of a grinder, a blank-holder, a spindle supporting the latter, a bearing for said spindle, 25 means for rolling said bearing toward and from the grinder, a gear-wheel on said spindle, mechanism carried by said bearing and engaging the gear-wheel for rotating the spindle in its bearing, a locking device carried by 30 said bearing for locking said mechanism, a movable member mounted in a fixed bearing for operating said device, and a flexible and extensible connection between said member and said device.

13. In a machine for generating gear-teeth on hardened toothed blanks, the combination of a grinder, a blank-holder, means for rolling said holder toward and from the grinder, mechanism for rotating the holder on its axis 40 independently of its rolling motion to index the blank, a continuously-rotating shaft, and a part driven thereby and operating intermittently on said mechanism, for driving the mechanism.

14. In a machine for generating gear-teeth on hardened toothed blanks, the combination of a grinder, a blank-holder, means for rolling said holder toward and from the grinder, mechanism for rotating the holder on its axis 50 independently of its rolling motion to index the blank, a locking device for locking said mechanism, a continuously-rotated shaft, and a part driven thereby and operating intermittently on said locking device, for actuating the same.

15. In a machine for generating gear-teeth on hardened toothed blanks, the combination of a grinder, a blank-holder, a spindle supporting the same, a bearing therefor, means 60 engaging said bearing for causing axial rotation thereof when lateral movement is imparted to it, a slide carrying said bearing, and means for reciprocating said slide, whereby the blank-holder is caused to roll toward and 65 from the grinder.

16. In a machine for generating gear-teeth on hardened toothed blanks, the combination

of a cutter-holder, means for imparting a reciprocating rolling motion thereto, a grinding-wheel, a bearing journaling said wheel, and 70 means for adjusting said bearing in the arc of a circle whose center is a point reached by the axis of the cutter-holder in its reciprocation.

17. In a machine for generating gear-teeth 75 on hardened toothed blanks, the combination of a cutter-holder, means for imparting a reciprocatory rolling motion thereto, a grinding-wheel, a bearing journaling said wheel, a member supporting said bearing and adjustable in the arc of a circle whose center is a 80 point reached by the cutter-holder in its reciprocation, and means for adjusting the bearing on said member to move the wheel radially with respect to said point. 85

18. In a machine for generating gear-teeth on hardened blanks, the combination of a blank-holder, a grinding-wheel representing a generating gear-tooth, means for imparting a relative movement to said holder and grinding-wheel in the relation of intermeshing gears, and a device for truing the surface of the grinding-wheel, said device being mounted for movement in the generating-surface, and the grinding-wheel being mounted for 95 movement of its generating-face toward said device. 90

19. In a machine for generating gear-teeth on hardened toothed blanks, the combination of a cutter-holder, a bearing therefor, means 100 for imparting a lateral reciprocatory movement to said bearing, a member having a connection with said bearing causing it to roll when thus reciprocated, and means for moving said member longitudinally at a predetermined rate during the reciprocation of the bearing. 105

20. In a machine for generating gear-teeth on hardened toothed blanks, the combination of a cutter-holder, a bearing therefor, means 110 for imparting a lateral reciprocatory movement to said bearing, a member having a connection with said bearing causing it to roll when thus reciprocated, means for moving said member longitudinally at a predetermined rate during the reciprocation of the bearing, and provisions for adjusting said means to vary the rate of movement of said member. 115

21. In a machine for generating gear-teeth 120 on hardened toothed blanks, the combination of a cutter-holder, a bearing therefor, means for imparting a lateral reciprocatory movement to said bearing, a member having a connection with said bearing causing it to roll 125 when thus reciprocated, means for moving said member longitudinally at a predetermined rate during the reciprocation of the bearing, and provisions for reversing said means to produce said movement in the same 130 direction with the movement of the bearing, or opposite thereto.

22. In a machine for generating gear-teeth on hardened toothed blanks, the combination

of a cutter-holder, a bearing therefor, a slide carrying said bearing, means for reciprocating said slide, a member having a connection with said bearing causing it to roll when thus reciprocated, a lever connected with said member, and a guide on the slide engaged with said lever.

23. In a machine for generating gear-teeth on hardened toothed blanks, the combination of a cutter-holder, a bearing therefor, a slide carrying said bearing, means for reciprocating said slide, a member having a connection

with said bearing causing it to roll when thus reciprocated, a lever connected with said member, a guide on the slide engaged with 15 said lever, and means for inclining said guide to either side of its path of motion.

In testimony whereof I have affixed my signature in presence of two witnesses.

EDWIN R. FELLOWS.
